JOHN W. NEWTON, OF GENEVA, WISCONSIN.

Letters Patent No. 96,829, dated November 16, 1869; antedated November 1, 1869.

IMPROVEMENT IN DRAGS.

The Schedule referred to in these Letters Patent and making part of the same.

To all whom it may concern:

Be it known that I, JOHN W. NEWTON, Geneva, in the county of Walworth, and State of Wisconsin, have invented a new and improved Drag; and I do hereby declare the following to be a full, clear, and exact description thereof, sufficient to enable those skilled in the art to fully understand the same, reference being had to the accompanying drawings, forming part of this specification, and in which my invention is illustrated by a perspective view.

Before plowing, it is preferable to remove or loosen the stubble, vines, or turf which usually encumbers old land.

My invention is an improved implement for this purpose; and

It consists of a number of teeth set in a stock, which is provided with a braced tongue and a curved bow or handle.

In the drawings—

Similar letters of reference indicate corresponding parts in the several figures.

A, in the drawings, represents the stock of my drag, in which is set a number of long pointed teeth, a.

B is the tongue, fitted on to the stock A, as shown, and secured thereto by means of the strap b, attached to the front of the stock, or by means of a pin, or one of the teeth a passing downward through the rear end of the tongue and into the stock. If desired or necessary, to render the attachment of the tongue more secure, both the pin and strap may be used.

The tongue is strengthened and rendered rigid by metallic braces c c, connecting it with the stock, as clearly shown.

C is a bow or handle, of wood or metal, set in the stock, and serving as a means whereby the latter may be lifted over corn-stalks or other impediments to progress.

The field is traversed with this drag, which penetrates the soil sufficiently to catch into the roots of the turf, stubble, or vines, and tear them up.

The torn-up roots are gathered by the teeth, and may be thus drawn into heaps or entirely out of the way, leaving the soil clear and open for the easy and effective passage of the plow.

I would here state that the pole or tongue may be dispensed with, and shafts or other draught-attachments substituted in its place. Therefore I do not limit myself to the tongue and braces, but I prefer the construction shown and described.

Constructed as above described, a cheap, simple, and durable implement is produced, which is well adapted to work effectually in preparing land for plowing.

Having thus described my invention,

What I claim as new, and desire to secure by Letters Patent, is—

The straight, rigid-toothed drag, consisting of the stock A, teeth a a, braces c c, and curved bow or handle C, all constructed, arranged and operated in the manner and for the purpose set forth.

To the above specification I have signed my name, this 5th day of February, 1869.

JOHN W. NEWTON.
